UNITED STATES PATENT OFFICE.

EMERSON B. MOSELEY, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,141,405.

Specification of Letters Patent.

Patented June 1, 1915.

Application filed July 30, 1908. Serial No. 446,185.

To all whom it may concern:

Be it known that I, EMERSON B. MOSELEY, a citizen of the United States, residing at Alliance, in the county of Stark and State 5 of Ohio, have invented certain new and useful Improvements in Filing Appliances, of which the following is a specification, reference being had therein to the accompanying drawings.

10 This invention relates to filing appliances and more particularly to that class of such devices in which paper or bill carrying frames or leaves are mounted in a portable supporting base that is adapted to be set 15 into a case when the appliance is in use, and to be easily removed from the case, so that only the frames or leaves and their base or support may be placed in a vault or other place for safe or convenient storage.

20 The invention has for its object to improve appliances of this kind in the several particulars to be hereinafter pointed out.

In the accompanying drawings, Figure 1 is a side view of a filing appliance embodying my improvements, it being represented as mounted in a case, parts of which are shown in section. Fig. 2 is a plan view as seen from above or in front of the base or support in which the bill holding frames or leaves are mounted, the parts of the base being represented in the positions occupied by them when the appliance is in use. Fig. 3 is a view similar to Fig. 2 except that it represents the parts of the base or support 30 closed together and occupying the positions assumed when an appliance is removed from the case and is ready for storage. Fig. 4 is an end view of the support or base when its parts are in positions indicated in Fig. 3, the 35 leaves or bill frames being represented in this view. Fig. 5 is a view, partly in front elevation and partly in section, illustrating the method of mounting a bill frame. Fig. 6 is a sectional view taken on the line 6—6 40 of Fig. 5. Fig. 7 is a detail view illustrating the method of applying the separating or division strips to the bill carrying frames or leaves. Fig. 8 is a detail sectional view illustrating the method of applying the sep-

arating or division strips to the bill carrying 50 frames.

In the accompanying drawings, 2 indicates the base portion of a case adapted to receive an appliance embodying my invention. The case may be of any suitable construction and need not therefore be illustrated or described in detail. In Fig. 1 of the drawings is represented its rear vertical wall 3, and top 4, which latter is hinged to a horizontal cross piece 5. Upon the latter is supported a triangular shaped block 6, adapted to serve as a rest or support for the base in which are mounted the hinged bill holding frames or leaves of the appliance. The block or rest 6 is shaped to support the 65 base for a group of paper or bill holding frames or leaves with their upper edges exposed one above the other from front to rear of the series, as is common in devices of this character.

70 7 indicates as an entirety a paper or bill holding frame or leaf. In its general features of construction it is of a well known type, consisting of a plate 8, preferably of thin metal supported at its lower or hinged 75 edge upon a cross rod or shaft 9, around which the edge of the plate 8 is preferably turned as a ready means of attaching the plate to the rod. The frame is divided into a number of vertical sections by strips 10, 80 the strips on adjacent frames lying opposite each other, with their edges preferably in contact when the frames or leaves are folded, as represented in Figs. 1 and 4. The outermost frames of a group or series constituting a single appliance preferably have strips applied to their inner surfaces only, while the intermediate frames or leaves preferably have them on both surfaces. The sections of the frames, between the strips 10, 85 90 are provided with means for holding the account slips, such as spring clips, but as these constitute no part of the present invention and are well known in the art they are not illustrated.

95 Each leaf or bill holding frame 7, is supported in an individual base piece 11, consisting preferably of a strip of metal of a

width approximately equal to the thickness of a bill carrying frame and having up-turned ends 12, 12'. In the end 12 of the base piece, there is mounted a bearing pin 13 having a cone shaped end adapted to be seated in a recess formed therefor in the end of a rod 9. This pin 13 is preferably riveted in place. In the opposite up-turned portion 12' of the base piece, there is mounted another bearing pin 14, which is preferably adjustable by being screw threaded. Its end is cone shaped or otherwise fitted to constitute an end bearing for the adjacent end of the rod 9. The means described for pivotally mounting the bill carrying frames permits any frame of the set to be separately put in place or removed, and supports it in such manner that it is free to move with little friction, and at the same time permits the bearings to be adjusted so that there shall be practically no lost motion in the pivotal supports.

The springs 15, which operate to counter-balance the leaves or bill carrying frames 25 and hold them in upright position, are preferably coiled about the rods 9, portions of the plates or sheets 8 being cut away at 16 to accommodate them. Each spring bears at one end against some relatively stationary 30 part, such as a base piece 11, and at its other end against a swinging bill carrying frame 7.

The bill frames are provided at their edges with strips 17, which serve both to strengthen and separate them and to give a 35 finished appearance thereto. The inner or lower ends of these strips are formed into bearings 18, adapted to rest upon the rod or cross shaft 9. This construction largely relieves the strain incident to swinging a 40 frame on its pivot from the thin plate 8.

As stated, each bill carrying frame is mounted in an individual support or base piece 11. These, in number corresponding with the number of frames in an appliance, 45 are united in such manner that they may be separated sufficiently to allow the leaves or frames 7 to lie close together in an upright position when the base frame is inclined, as represented in Figs. 1 and 2, or be moved 50 close together side by side, as represented in Figs. 3 and 4, when the leaves are removed from the case for storage.

19, 20, 21, 22, and 23 indicate cross pieces secured to the supports or base pieces 11, and 55 serving to unite them and at the same time maintain them in parallel relation, one with the other. The base frame illustrated in Figs. 2 and 3 consists of seven supporting bars or pieces 11, united by five cross plates 60 or strips at each end. Each cross piece is rigidly secured to a supporting bar 11, by a rivet 24, or other suitable means. The cross pieces are represented as follows: 19 as

being secured to the lowermost bar, 20 to the third bar, 21 to the fourth bar, 22 to the 65 fifth, and 23 to the seventh or uppermost bar. Each cross piece is arranged to overlie at least, and preferably, two bars 11, besides the one to which it is rigidly secured when the frame is expanded, as indicated in 70 Fig. 2, thus materially stiffening the frame. The cross bars or certain of them, are slotted as represented at 25, and through these slots extend headed pins 26, carried by the leaf supporting bars 11. The cross piece 19 75 has two slots 25, the inner one about twice as long as the outer one in which move pins 26, carried respectively by the second and third bars 11. The cross bar 20 has preferably but a single slot in which a pin carried 80 by the fourth bar 11 moves, while the middle cross piece 21 need not be slotted at all, although its ends overlie the third and fifth bars 11. Of course, this cross piece 21 could be slotted and thus directly connected with 85 the third and fifth supporting bars, but this ordinarily is not found to be necessary. Cross pieces 22 and 23 are slotted in a manner similar to parts 19 and 20, although the slots are inversely arranged. The cross 90 pieces are supported so as to lie in engagement, edge to edge, thus forming convenient means for maintaining the supporting bars 11 in parallelism under all conditions.

27, 27 indicate a pair of latches pivoted at 95 28 to an outermost bar of the supporting frame and adapted to engage either with pins 29, 29, or pins 30, 30, carried by the supporting bar at the edge of the frame opposite the bar to which the latches are pivoted. The pins 29 are located toward the center of the bar 11, so that when the latches engage therewith they extend diagonally across the supporting frame and hold it in 100 a closed position. But the pins 30 are so located that the latches extend across the bars 11 at right angles, and hold the supporting frame in extended position, as indicated in 105 Fig. 2.

I have devised novel means for applying 110 the strips 10 to the leaves or bill holding frames, which I will now describe.

In the plate or sheet 8 of each bill frame are formed a number of perforations, preferably oblong in shape, and arranged along 115 the lines to be occupied by the strips 10. Into these perforations are inserted small pieces of metal 32, shaped in cross section to fit the apertures quite closely and when inserted therein to extend beyond both the opposite surfaces of the plate. The strips 10, themselves, are formed of metal bent into U-shape transversely and set over the projecting ends of the pieces 32, to which they are united in any suitable manner, as by being crimped thereto, as indicated at 120 33. It

will thus be seen that the pieces 32 constitute anchor blocks to which the opposite strips 10 are united, and by which they are held in proper position against the opposite faces of the surfaces of the bill holding frame.

To those skilled in the art of making filing appliances, many alterations in construction and widely differing embodiments and applications of my invention will suggest themselves, without departing from the spirit and scope thereof.

My disclosures and the description herein are purely illustrative, and are not intended to be in any sense limiting.

What I claim is:

1. In a filing appliance, the combination of a series of frames, a series of bases, one for each frame, means for pivoting each frame to an adjacent base, and two sets of paralleling bars, each bar of each set being secured to a base and extending to or beyond the means which secure an adjoining bar to a base and having sliding engagement with an adjoining bar or bars, the bars of one set being arranged side by side relative to each other oppositely to the relative arrangement of the bars of the other set.

2. In an accounting appliance, the combination of a series of bill holding leaves, a series of bases, one for each leaf, means for pivoting the leaves upon the bases, two series of paralleling bars, each series being arranged near the opposite ends of the bases, and means for securing each of said bars of a series to an adjacent base, each of said bars extending to or beyond the means which secure an adjoining bar to a base when the bases and leaves are in operative position.

3. In an accounting appliance, the combination of a series of bases, a series of bill holding leaves one for each base and arranged parallel thereto, means for pivotally mounting each of said leaves upon a base, and a series of cross bars each secured to certain of the said bases, arranged to permit the bases to move relative to each other but maintaining them in parallelism, each of said cross bars extending transversely across three of said bases, when the bases and leaves are in operative position, and means carried by one end base and having detachable connection with the other end base for securing the leaves and bases in separated position or in closed position.

4. In an accounting appliance, the combination of a series of bases, a series of bill holding leaves, means for pivotally mounting each of said leaves upon a base, and means for maintaining the said bases in parallelism and permitting them to be separated from each other, the said means comprising a series of cross bars slidably mounted rela-

tive to each other, and means for securing each of said bars to a base, each of said bars extending to or beyond the means for securing an adjoining bar to a base, and means carried by one end base and having detachable connection with the other end base for maintaining the bases in closed position when the leaves and bases are arranged for storage, or in separated position when the leaves and bases are arranged for operation.

5. In an account register, the combination of a set of swinging bill-holding frames, a supporting base therefor comprising a bar for each frame having up-turned ends in which the frame is pivoted, cross pieces located near the respective ends of the supporting frame, each cross piece being rigidly connected to one of the supporting bars and overlying another, the cross pieces having sliding connection with those bars to which they are not rigidly secured, and arranged while connecting the bars to permit them to be either separated or brought close together side by side, and adjustable latches arranged, when adjusted to one position, to hold the bars separated and when adjusted to another position to hold them together side by side, substantially as set forth.

6. In a filing appliance, a bill-holding frame comprising a sheet or plate against which series of slips or papers are removably held, a pivot bar on which an adjacent sheet is supported, the said sheet being secured to said bar along one edge and strengthening ribs at the opposite side edges of each sheet, the said ribs being formed with bearings 18 resting upon the pivot rod, substantially as set forth.

7. In a filing appliance, the combination of a series of sheet metal holding frames, a series of pivot rods, one for each frame, each of said frames being connected to its rod along one edge and formed with cutaway portions extending inwardly along its hinged edge from its opposite sides, means for supporting the pivot rods, springs mounted in said cutaway portions in each frame and coiled around the adjacent pivot rod for counterbalancing the frame, and strengthening ribs fixed to the opposite side edges of each frame, the said ribs being provided with bearings resting upon said rods.

8. In an account register, a bill-holding frame comprising a plate against which the account slips are held, connecting pieces secured to the said plate and projecting beyond the surface thereof, and a separating strip arranged to straddle the said connecting pieces and to be secured thereto, substantially as set forth.

9. In an account register, a bill-holding frame comprising a thin sheet or plate against which the account slips are held and

in which are formed a series of perforations, connecting pieces set into the said perforations and extending beyond the opposite faces of the plate, and separating ribs adapted to straddle the said connecting pieces and to be secured thereto, substantially as set forth.

In testimony whereof I affix my signature, in the presence of two witnesses.

EMERSON B. MOSELEY.
